MEANS FOR TRANSPORTING HEAVY LOADS

Edward E. Bollinger, Lancaster, Pa.

Application October 21, 1944, Serial No. 559,779

6 Claims. (Cl. 214—113)

1

This invention relates to means for transporting heavy loads in a manner materially reducing the time and labor as now generally required in the moving or shifting of comparable loads, and it is primarily an object of the invention to provide a means of this kind which is of a character particularly designed and adapted for use in connection with an industrial lift truck.

It is also an object of the invention to provide a means for the purpose desired comprising a turntable to be operatively engaged with the load carrier or fork of an industrial lift truck and for coaction with one end portion of the load, together with a dolly for operative coaction with the opposite end portion of the load.

An additional object of the invention is to provide a means for moving or transporting heavy loads comprising the use of two load supporting elements, one of which constitutes a "fifth wheel" structure for operative engagement with the fork or load carrier of an industrial lift truck and with the load and the other support constituting a dolly for operative engagement from below with the load and wherein each of such supports is of a character to be effectively engaged with a load supporting skid or with a flat surface portion of the load.

The invention consists in the details of construction and in the combination and arrangement of the several parts of my improved means for transporting heavy loads whereby certain important advantages are attained, as will be hereinafter more fully set forth.

In order that my invention may be the better understood, I will now proceed to describe the same with reference to the accompanying drawings, wherein:

Figure 1 is a fragmentary view illustrating a front end of a load coupled to the load fork or carrier of a lift fork;

Figure 2 is a fragmentary view of the opposite end portion of the load having engaged therewith dollies embodying the present invention;

Figure 3 is a diagrammatic view in top plan illustrating a means embodying the present invention and as illustrated in Figures 1 and 2;

Figure 4 is a view in bottom plan of the fifth wheel structure embodying the invention;

Figure 5 is a sectional view taken substantially on the line 5—5 of Figure 4;

Figure 6 is a view in top plan of the structure as illustrated in Figure 4 with portions broken away;

Figure 7 is a fragmentary view in bottom plan

2

illustrating a fifth wheel structure embodying another embodiment of the invention;

Figure 8 is a fragmentary view partly in elevation and partly in section of the assembly illustrated in Figure 7;

Figure 9 is a view in bottom plan of a dolly as herein embodied;

Figure 10 is a view in top plan of the dolly as illustrated in Figure 9; and

Figure 11 is a fragmentary sectional view taken substantially on the line 11—11 of Figure 2.

Generally, in the handling of heavy and large loads such as machinery, considerable time and labor are required to move or shift the same from one desired location to another although such an operation is materially facilitated by the use of any of the well known types of industrial lift trucks. The present invention embodies means wherein, in conjunction with one of such industrial lift trucks, the required transportation of heavy or large loads may be accomplished with a material saving in both labor and time.

As illustrated in the accompanying drawings, such means embodies the use of two forms of supporting members A and B, the member A constituting a "fifth wheel" structure and the member B a dolly. The member A is directly used in connection with the load carrier or fork F of an industrial truck while the member B is suitably positioned beneath the load to be transported in proper relation with the member A when engaged with the load.

The industrial lift truck may be of any preferred type and no part thereof forms part of the present invention.

The member A comprises an elongated member 1 of desired dimensions and which is provided at desired spaced points thereon with the underhung loop members 2 through which are directed the arms 3 of the load carrier or lifting fork F when the member A is in applied or working position.

Threading through a wall of each of the loop members 2 is a binding screw 4 for coaction with a portion of a fork arm 3 within the loop member to lock the member A upon the load carrier or fork F. It is believed to be obvious, however, that other means may be employed to effect the desired locking of the member A in applied or working position upon the load carrier or fork F.

The central portion of the member 1 is provided with an opening 5 through which is adapted to be freely inserted from above a king bolt 6 depending from and rigid with the central portion of the bolster A' of the member A. The

upper portion of the bolt 6 is surrounded by an outstanding shoulder 7 having contact from above with the elongated member 1 whereby the bolster A' is supported upon the member 1 yet free to rotate with the king bolt 6 as the axis.

Engaged with the bolt 6 below the member 1 is a holding member or nut 8 locked to the bolt 6 by a removable pin 9 inserted through both the member or nut 8 and the bolt 6. It is believed to be obvious that the mounting of the bolster A' upon the elongated member 1 is such as to permit ready separation or assembly.

The bolster A', as herein comprised, is substantially V-shaped in form from end to end with its walls 10 substantially in right angular relation although this angularity may be otherwise as deemed best. This particular formation of the bolster A' permits the same to be engaged from below to the best advantage with the usual cross sills 11 or the like as comprised in the general type of foundations now employed for placing machinery or other heavy loads to be transported. However, the upper or outer margins of the walls 10 are continued by the outstanding flanges 12 at right angles to the longitudinal axis of the king bolt 6 with the top flat faces substantially coplanar. This permits the bolster A' to be used when required in connection with a flat part of the load to be transported.

The opposite end portions of the outstanding flanges 12 have threaded therethrough from below the heavy bolts 14 which can also be employed to advantage for effective engagement from below with the load to be transported when the use of the bolster A' may otherwise not be effective. Under certain conditions it is of importance to have the bolster A' effectively tied to the load and for this purpose the walls 10 at their central portions are provided with the outstanding arms 15 provided in their free extremities with the claws 16, to which a chain or other flexible element may be locked, said chain or flexible element, of course, being disposed over or around a foundation sill or other part of the load with which the member A is employed.

The member or dolly B, as herein disclosed, comprises the side members 17 substantially V-shaped in form and having their upper edges provided with the upstanding penetrating teeth 18 to facilitate effective engagement with a cross sill or other part of the load to be transported. The side members 17 are maintained in desired spaced relation by the interposed flat top plates 19 which permit the member or dolly B to be firmly held in position.

Underlying the plates 19 and in swiveled connection therewith are the caster wheels 20. There is a single caster wheel at each end of the member or dolly B with the wheel 20 at one end to one side of the transverse center of the member B and the second wheel 20 at the opposite side of the transverse center. This arrangement of the caster wheels 20 assures the effectiveness of the member B in use and functions particularly to prevent undue tilting of the load resting upon the member B.

The intermediate portion or head 21 of the yoke 22 for each of the caster wheels is provided therearound with the equidistantly spaced openings 23 adapted to be selectively brought into register with an opening 24 in the top plate 19 thereabove and a locking or holding pin 25 is engaged through said registering openings to lock the caster wheels against rotation. It has been fully demonstrated in practice that when the

load is in transit, the locking of one of the caster wheels 20 of each of the members B, with the second caster wheel free to rotate, the load being drawn by the industrial lift truck will travel straight ahead therewith yet properly turn with the steering of the lift truck. Of course, when it is desired to place or remove the load within a restricted area, both of the caster wheels 20 of the member B should be free to rotate as under such conditions it often is found necessary that manual lateral pressure be imposed upon the load being transported to facilitate the desired handling.

The V formation of the side members 17 of the member B permits the member or dolly B to be effectively employed in connection with a transverse sill or kindred part of the load while the plates 19 permit the effective use of the member or dolly B with a flat surface of a part of the load. These plates 19 are provided with the suitably positioned upstanding penetrating members 25 to facilitate the desired coaction of the member or dolly B with a load.

As hereinbefore stated, it is the general practice in connection with heavy loads, such as machinery or the like, to place the same on a foundation including a transverse sill. In the embodiment of the invention as illustrated in Figures 7 and 8 of the drawings, there is suitably secured to the under surface of one of said transverse sills a plate 26 from the central portion of which depends the rigid king pin 27 which is adapted to be disposed through the opening 5 of the elongated member 1 and maintained in swiveled connection with the member 1 by the member or nut 28 threading upon the king pin 27 from below the member 1. In this arrangement the plate 26 and its king pin 27 remains as a part of the foundation upon which the load to be transported is initially placed and when so used, there is obviated the necessity of using the bolster A' hereinbefore referred to.

In practice, the lift truck is moved into position at one end of the load, which may be in the form of a crated machine or the like and, by the use of the load carrier or the fork F, the load is lifted at one end sufficiently to allow the dollies B to be properly placed under the load. The opposite end of the load remains, of course, upon the floor. The fork of the lift truck is then lowered until the load comes to rest upon the dollies.

The member A is then mounted upon the fork F of the load carrier by the extension of the arms of the fork through the loop members 2 and the binding screws 4 are then tightened up to secure the member A on the fork. The supported member may then be moved beneath a suitable portion of the load at the opposite end thereof from the dollies B or if the load is not of such construction as to permit the member A to be shifted under it, the load is first raised by the lift truck, before mounting the member A upon the fork, and suitably blocked with timbers at the proper elevation to allow for the introduction of the member A therebeneath, after such member has been mounted upon the fork in the manner described. The arms of the lift truck fork are then raised to bring the member A into engagement with the under side of the load and the load is lifted so that the blocking may then be removed and the load can be freely supported by the truck fork and by the pair of dollies at the opposite end of the load. The truck can then readily draw the load to the desired destination.

It is to be stated that by the use of the inven-

tion as herein embodied, the services of only one man are required other than the driver of the truck and that transportation or shifting of a load of considerable weight can be effected in a very short period of time.

From the foregoing description it is thought to be obvious that a means for transporting heavy loads constructed in accordance with my invention is particularly well adapted for use by reason of the convenience and facility with which it may be assembled and operated.

What is claimed is:

1. A load supporting unit for mounting on a vertically movable load carrier of an industrial lift truck, comprising a member, means for securing the lower member to the lift truck, a king bolt, means forming an upper member for connecting the king bolt to the load to depend therefrom, the lower member having an opening to receive the king bolt whereby said lower member and the load are swivelly coupled.

2. A load supporting unit for mounting on a vertically movable load carrier of an industrial lift truck comprising a member, means for securing the member to the load carrier, a bolster to engage the bottom of the load, and a king bolt depending from the bolster, the member having an opening to receive the king bolt to permit the member and the bolster to be swivelly connected.

3. A load supporting unit for mounting on a vertically movable load carrier of an industrial lift truck, comprising a member, means for securing the member to the load carrier, a bolster to engage the bottom of the load, and a king bolt depending from the bolster, the member having an opening to receive the king bolt to permit the member and the bolster to be swivelly connected, said bolster having lateral arms to facilitate coupling the bolster to the load.

4. A load supporting unit for mounting on a vertically movable load carrier of an industrial lift truck, comprising a member, means for securing the member to the load carrier, a bolster to engage the bottom of the load, and a king bolt depending from the bolster, the member having an opening to receive the king bolt to permit the

member and the bolster to be swivelly connected, said bolster at predetermined points having bolts threading therethrough from below for contact with the bottom of the load.

5. A load supporting unit for mounting on a vertically movable load carrier of an industrial lift truck, comprising a member, a bolster of V channel form to engage the bottom of the load, a king bolt integral with and depending from the ridge of the bolster, the member having an opening to receive the king bolt to permit the member and the bolster to be swivelly connected, and means for detachably securing the member on the load carrier.

member and the bolster to be swivelly connected, said bolster at predetermined points having bolts threading therethrough from below for contact with the bottom of the load.

5. A load supporting unit for mounting on a vertically movable load carrier of an industrial lift truck, comprising a member, a bolster of V channel form to engage the bottom of the load, a king bolt integral with and depending from the ridge of the bolster, the member having an opening to receive the king bolt to permit the member and the bolster to be swivelly connected, and means for detachably securing the member on the load carrier.
